SAFETY SWITCH

Henry C. Pierson, Quincy, Fla., assignor of one-third to Reginald Wayne Locklin, River Junction, Fla., and one-third to Henry Earl Pierson, Quincy, Fla.

Application November 16, 1933, Serial No. 698,333

1 Claim. (Cl. 200—52)

This invention relates to safety switches of the kind used on automobiles for automatically interrupting the ignition circuit in the event the automobile is turned over and thereby eliminate the danger of injury by fire.

The object of the invention is to provide a switch of this character for grounding the ignition circuit upon the happening of the above contingency; and further to simplify the construction of, and render more positive the operation of such safety devices.

In the drawing:

Figure 1 is an elevational view of the switch.
Figure 2 is a sectional view therethrough.

Figure 3 is a horizontal section taken on line 2—3 of Figure 2.

Figure 4 is a view of the switch in an inclined or canted position, with parts broken away to illustrate the operation and

Figure 5 is a wiring diagram.

Referring to the drawing by numerals the invention, in the illustrated embodiment thereof, comprises a substantially sealed casing 10 of conductive material, having a cap 11, of di-electric material secured on the top thereof by suitable fastening elements 12.

A metallic socket 13 is embedded centrally within the cap 11, and has a retaining flange 14 integral therewith to firmly secure the socket.

30 A pendulum 15 is provided with a ball-head 16 engaged in the socket as shown to suspend the pendulum in the casing for universal movement. Integral with socket 13 is a binding post 17 that projects through the top of the cap and to which the wire 18 is secured by the nut 19 in the conventional manner.

To protect the above electrical connection an elastic cap or sleeve 20 is provided as shown clearly in Figure 2.

40 For mounting the device in a vertical position on a suitable part 21 of the automobile, as for example, the instrument board, vertically spaced bolts 22 are provided on the casing 10.

In Figure 2 the device is shown mounted, and 45 in Figure 5, B indicates the battery, 23 the ignition switch, 18 the wire leading from one side of the switch to the coil 24, while 25 indicates the distributor, all of which is conventional and is embodied in automobile ignition systems.

50 Normally the pendulum 15 is perpendicular. Should however, as for example, in the event of an accident, the automobile turn over, and the ignition switch 23 is closed a grounding of the

circuit will automatically take place, since the pendulum will swing into engagement with the wall of casing 10 as shown in Figure 4 thus grounding the circuit, as is thought apparent. The circuit being grounded in this manner the 5 motor will stop and the danger of fire thus overcome.

The frictional engagement between ball 16 and socket 13 will be such as to restrain material 10 swinging movement of the pendulum, as might otherwise result from vibration. Also the socket 13 is provided with an internal conical formation 26, the point of which is slightly spaced from the ball 16 and slightly to one side of the vertical diameter of the ball. Thus if the vehicle 15 should turn completely upside down, the ball, resting on this point, would rotate under the action of the weight 15 and thus the weight would strike the casing and thus ground the circuit and the purpose of same is to guard against 20 the pendulum remaining vertical should the automobile turn completely up-side-down, and, under such circumstances to insure a swinging of the pendulum through an arc sufficient 25 to engage the wall of casing 10 for grounding the circuit.

Having thus described my invention, what I claim is:

A safety switch comprising a casing of conductive material having its upper end open, a 30 cap closing the open end of the casing and formed of non-conducting material, a centrally arranged socket member having its upper portion embedded in the cap with its upper end spaced from the top surface of the cap, the 35 socketed part of the member depending into the casing, a ball fitting in the socket and the end wall of the socket being pressed inwardly into engagement with the ball to hold the ball in place and to prevent too free movement of the 40 ball, a stem connected with the ball and depending therefrom into the casing, a weight connected with the lower end of the stem, said weight engaging the casing when the casing is tilted, a binding post connected with the upper end of 45 the socket member and passing through the upper surface of the cap, and a conical projection on the socket member and depending into the socket thereof and forming a pointed seat for the ball when the casing is inverted whereby the 50 ball will rotate and the weight will engage the casing.

HENRY C. PIERSON.
